MOISTURE SEPARATING TANK

John D. McKenney, South Laguna, and Thomas R. Rumsey, Inglewood, Calif., assignors to Royal Industries, Inc., Pasadena, Calif.

Filed Oct. 12, 1971, Ser. No. 188,640

Term of patent 14 years

Int. Cl. D23—01

U.S. Cl. D23—2

FIG. 2

FIG. 1 is a side elevational view of a moisture separating tank showing our new design; and

FIG. 2 is an elevational view taken from one end thereof, the opposite end being the same as the end shown.

We claim:

The ornamental design for a moisture separating tank, substantially as shown and described.
